UNITED STATES PATENT OFFICE.

JERRY JAY DUNN, OF GREENVILLE, PENNSYLVANIA, ASSIGNOR TO SHELBY STEEL TUBE COMPANY, OF PITTSBURG, PENNSYLVANIA, A CORPORATION OF NEW JERSEY.

CROSS-ROLLING APPARATUS.

No. 829,953.

Specification of Letters Patent.

Patented Sept. 4, 1906.

Application filed April 19, 1905. Serial No. 256,374.

To all whom it may concern:

Be it known that I, JERRY JAY DUNN, of Greenville, Mercer county, Pennsylvania, have invented a new and useful Cross-Rolling Apparatus, of which the following is a full, clear, and exact description, reference being had to the accompanying drawings, forming part of this specification, in which—

Figure 1 is a small diagrammatic plan view of my improved apparatus. Fig. 2 is a partial top plan view, on a larger scale, showing the parts in position at the beginning of the cross-rolling operation. Figs. 3, 4, and 5 are partial horizontal sections showing in Fig. 3 the parts in position before beginning the operation, in Fig. 4 at the beginning of the operation, and in Fig. 5 at the end of the operation; and Fig. 6 is a vertical cross-section of Fig. 4.

My invention relates to the "reeling" or cross-rolling of tubes.

In the cross-rolling of seamless tubes after rolling the hollow blank on a plug-mill difficulty has been experienced in handling the plug or mandrel which was held on the mandrel stem or support between the rolls. Where this ball or mandrel was secured to the mandrel-rod, it was necessary either to pull the ball or plug through the tube after the same had been passed through the machine or else withdraw the bar or stem with its plug detached from the tube in the opposite direction. Either operation reduces the output and capacity of the machine, interfering with the supports for the bar or mandrel-rod and requiring extra labor in operation.

My invention overcomes these difficulties, and it consists in providing in a cross-rolling mill a mandrel stem or support and a detachable ball, plug, or mandrel which may be dropped from the end of the mandrel-rod after the tube has passed the reeling-mill.

It also consists in so shaping the ball or mandrel and the end of the mandrel-rod that the mandrel or ball will properly seat itself on the mandrel-rod by the action of the entering tube.

It further consists in the construction and arrangement of the parts, as hereinafter more fully described and claimed.

In the drawings, 2 and 3 represent the positively-driven skew-rolls, which are inclined

in opposite directions, as in the ordinary cross-rolling mill.

4 indicates the mandrel-rod, and 5 the detachable mandrel or plug. I preferably form this plug with a conical recess in its rear end and make the plug in the general form of a projectile. The rod is preferably provided with an enlarged end portion 6, having a conical point or guide portion 7 projecting at its center. A shoulder is thus formed around the base of the point, against which the base of the mandrel-head may seat. The enlarged portion 6 of the mandrel-rod is preferably cylindrical and is larger than the rod proper, but preferably slightly smaller than the plug or ball 5. The size of the part 6 is so proportioned that when the plug and the part 6 lie in separated position upon the lower guide 8 the conical point on the mandrel-rod will be in proper position to enter the conical recess as the tube enters and forces the ball into seating position on the rod.

In the operation of the device the tube enters the cross-rolling mill over any suitable feed-table—such as shown at 9 in Fig. 1—and as its forward end engages the ball or mandrel 5 it forces it back from the position shown in Fig. 3 into the seating position on the mandrel-rod, as shown in Fig. 2. In addition to the lower guide-support 8 I preferably employ an upper corresponding guide 10, these guides being separated sufficiently to allow the tube to pass, but holding the mandrel and mandrel-rod loosely in place.

In Fig. 4 the parts are shown in position during the cross-rolling operation. At the end of the operation as the rear end of the seamless tube passes the mandrel the mandrel or ball jumps away from the end of the mandrel-rod, assuming a position same as shown in Figs. 3 or 5. As the part 6 of the mandrel-rod, is smaller than the inner diameter of the reeled tube, the mandrel-rod can be easily withdrawn by any suitable apparatus, such as shown at 11 in Fig. 1, leaving the plug in its position between the rolls. During the reeling operation the inside of the tube is smoothed and finished and grooves or scorings are removed. The side face of the ball or plug is so shaped that it holds the ball in proper position on the guide to be pushed into seating position as the tube enters.

The advantages of my invention result from the use of the mandrel-rod with a removable mandrel or ball between the rolls of a cross-rolling mill, also from the use of the self-seating ball and the support which holds it in place, while the mandrel-rod is removed. In the preferred form all manual handling of the mandrel or ball is done away with, as it is kept back by the operation as the rod leaves it and rests on the guide in position to be pushed into seating position again as the next tube enters.

Many variations may be made in the form and arrangement of the cross-rolls, the mandrel, the mandrel-head, the guides, &c., and the mill may be used for different purposes without departing from my invention.

I claim—

1. A cross-rolling mill having a guide between the rolls, and a mandrel-rod having a detachable mandrel or ball arranged to rest on the guide; substantially as described.
2. A cross-rolling mill having between the rolls a removable mandrel or ball, and a mandrel-rod normally detached from the ball and movable independently thereof, the front end portion of the rod and the rear portion of the mandrel or ball being so shaped as to cause self-seating of the ball on the rod on the entrance of the tube; substantially as described.
3. A cross-rolling mill having a removable mandrel-head, and a mandrel-rod movable independently of the head, said parts having an interfitting recess and pin connection ar-

ranged to cause automatic seating, and means for holding the head between the rolls when the rod is removed; substantially as described.

4. A cross-rolling mill having upper and lower guides between the rolls in combination with a mandrel-rod, and a removable mandrel or ball; substantially as described.

5. A cross-rolling mill having rolls, a mandrel-rod with an enlarged cylindrical front end, a removable mandrel-head of slightly larger diameter than the enlarged portion of the rod, and a guide between the rolls for the mandrel-rod; substantially as described.

6. In a cross-rolling mill, a supporting guide between the rolls, and a removable mandrel and mandrel-rod arranged to rest on the guide and having their adjacent ends arranged to seat and interfit as the tube passes through, the mandrel-rod being normally detached from the mandrel and movable independently thereof; substantially as described.

7. In a cross-rolling mill, a pair of horizontally-opposed rolls, a guide between them, a removable mandrel or ball arranged to rest on the guide, and a normally detached mandrel-rod having parts arranged to interfit with the mandrel as the tube passes through; substantially as described.

In testimony whereof I have hereunto set my hand.

J. JAY DUNN.
